UNITED STATES PATENT OFFICE

147,207

DESIGN FOR AN ENCASED POWER UNIT OF
AN ELECTRIC APPLIANCE OR THE LIKE

Harry S. Preble, Jr., New York, N. Y., assignor to
The A. C. Gilbert Company, New Haven, Conn.,
a corporation of Maryland

Application January 5, 1946, Serial No. 125,307

Term of patent 14 years

(Cl. D26—5)

To all whom it may concern:

Be it known that I, Harry S. Preble, Jr., a citizen of the United States, residing at New York, in the county of New York and State of New York, have invented a new, original, and ornamental Design for an Encased Power Unit of an Electric Appliance or the like, of which the following is a specification, reference being had to the accompanying drawings, forming part thereof.

Figure 1 is a plan view, Figure 2 is a front end view, Figure 3 is a rear end view, Figure 4 is a side view, Figure 5 is a view looking at the bottom, and Figures 6 and 7 are perspective views, respectively, of encased power unit of an electric appliance or the like showing my new design.

I claim:

The ornamental design for an encased power unit of an electric appliance or the like, substantially as shown.

HARRY S. PREBLE, JR.
